UNITED STATES PATENT OFFICE.

HINSDALE SMITH AND ARTHUR P. SMITH, OF SPRINGFIELD, MASSACHUSETTS.

METAL VEHICLE-BODY.

No. 869,025.

Specification of Letters Patent.

Patented Oct. 22, 1907.

Application filed April 2, 1907. Serial No. 365,902.

To all whom it may concern:

Be it known that we, HINSDALE SMITH and ARTHUR P. SMITH, citizens of the United States of America, residing at Springfield, in the county of Hampden and State of Massachusetts, have invented new and useful Improvements in Metal Vehicle-Bodies, of which the following is a specification.

This invention relates to improvements in vehicle bodies and particularly to improvements in metal bodies as at present used on automobiles.

Broadly the invention consists in providing the rear side of the seat portion with means for readily and securely attaching the upholstering material, as leather or fabric.

15 In the metal bodies for vehicles as heretofore constructed it has been customary to provide the same with a rolled upper edge in the rear part of the seat portion to which the upholstering was secured. This way of making the upper edge of the seat portion has 20 made it difficult and expensive to securely and quickly fasten the upholstering thereto. By the use of our improvement, hereinafter described, in which the substitution of a wooden rail or bow piece for the rolled metal edge, the upholstering can be readily secured to the metal body.

25 In the drawings which form a part of this application: Figure 1 is a perspective view showing a portion of the metal body, and the wooden bow piece, which is attached to the upper edge of the seat portion. Fig. 2 is a sectional view on the line 2—2 of Fig. 1 looking in the direction of the arrow, with a portion of the upholstering secured to the wooden bow-piece of the seat portion.

30 Referring to the drawing in detail, *a* designates that portion of the seat of the metal body to which my improvement relates,

b designates a beaded part of the seat portion of the body and immediately above the beaded portion is secured a molded bow-piece *c*, preferably made of

wood, to which the upholstering is to be secured. 40 This bow-piece is secured to the rear side of the seat portion of the metal body *a* by any suitable means, as the screws *d*.

The upholstering for the rear portion of the seat of the body is designated at *e*, and is carried up over the top 45 of the bow-piece *c*, as shown at the point *f*, and securely fastened to the rear side of the same by means of the tacks, designated at *g*, the filling material being designated at *h*.

The beaded portion *b* serves the double purpose of 50 strengthening the rear portion of the seat of the body and also as a bearing edge for the wooden bow-piece *c*.

It will be seen therefore that we have produced a structure that readily permits the upholstering material to be quickly and securely fastened to the metal body 55 portion of the vehicle and at a small expenditure of time and labor.

What we claim is:

1. In a vehicle body, the seat portion of the same having a bead formed therein, a bow-piece secured to the body 60 portion and at the rear side of the seat portion of the body; said bow-piece being of different material than the body portion whereby the upholstering material can be readily attached thereto.

2. In an improvement of the class described, the metallic 65 body and an attachment therefor for securing the upholstering thereto, said attachment being located at the rear side of the seat portion, and consisting of a molded bow-piece, a bead in the body portion, adjacent to the bow-piece as described.

3. In an improvement of the class described, a metal 70 body having a beaded portion near the upper edge of the seat thereof, a wooden bow-piece secured to the rear side and flush with the upper edge of the seat portion, and upholstering attached to the rear side of the bow-piece, 75 said bow-piece being adjacent to the upper side of the beaded portion.

HINSDALE SMITH.
ARTHUR P. SMITH.
